UNITED STATES PATENT OFFICE.

ERWIN M. HARLEY, OF TIFFIN, OHIO.

UMBRELLA.

SPECIFICATION forming part of Letters Patent No. 633,584, dated September 26, 1899.

Application filed May 25, 1898. Serial No. 681,716. (No model.)

To all whom it may concern:

Be it known that I, ERWIN M. HARLEY, a resident of Tiffin, in the county of Seneca and State of Ohio, have invented certain new and useful Improvements in Umbrellas; and I do hereby declare the following to be a full, clear, and exact description of the invention, such as will enable others skilled in the art to which it pertains to make and use the same.

10 My invention has relation to umbrellas, comprehending a simple and effective means for securing each umbrella-rib to the runner independently of the other ribs, thus permitting the removal and replacement of any 15 rib when necessary without disturbing the others.

The invention will first be described in connection with the accompanying drawings and then pointed out in the claim.

20 Figure 1 is a view in elevation of an umbrella constructed in accordance with my invention. Fig. 2 is a similar view, partly broken away and enlarged. Fig. 3 is a perspective view of the notch-collar to which the 25 upper ends of the ribs are attached.

Referring to the drawings, A represents the umbrella-stick, on which the runners B and collar C are placed and operated in the usual manner. In my preferred construction 30 (illustrated in the drawings) the collar is formed with a circumferentially arranged flange 1, horizontally slotted at 2 for a portion of its depth and vertically slotted at 3 back to the collar proper, this construction 35 resulting in two series of pins 4, each series lying in a plane at a right angle to the longitudinal axis of the umbrella-stick and proximate projections, one in each series, arranged in complementary pairs, as shown. The pins 40 are malleable, and each pair is adapted to be compressed upon a stud fixed to a rib or brace. For this purpose the ribs D and braces or 45 stretchers E, which are of usual construction, are each provided at the ends with short studs.

In assembling the ribs and a runner or a notched ring, as the case may be, the rib-heads are simply entered between two adjacent pairs of projections, with the studs each 50 between the members of a pair, no bending or modification of any of the parts being required for this purpose. The members of

each pair of projections are then compressed upon a stud, though obviously the compression of one projection could be made to hold 55 the stud with some degree of security.

The side walls of the slots 3 are parallel and in planes closely approximating a radial situation with respect to the stick. The outer faces of the pins 4 opposite said parallel slot-walls or 60 approximate pin-faces are inclined to the stick. The pins are arranged in groups of four, each comprising two pairs inclosing slots fitted by the ribs, the several groups being more widely separated from each other than are the pairs 65 in each group. It also results from the particular construction that the pins, though provided with parallel faces to closely receive the ribs, are comparatively thick at their bases and thin toward their outer ends, as 70 desirable for strength and for facility in bending. It may be noted that as both members of each pair can be bent less compression of the metal in each pin is required to effect the fastening. Further, the comparatively wide 75 opening between the groups affords convenient access to all the pins for repairs.

In securing the ribs in place the studs 5 are placed in the horizontal slot 2 of the flange 1, the enlarged end of the rib or stretcher lying 80 in the vertical slot 3. The ends of pins 4 of each upper and lower pair are then bent toward each other, firmly securing the rib or stretcher in place, all as shown in Fig. 3. By extending the horizontal slot 2 only a short 85 distance into the flange 1 I am enabled to limit the inward movement of the studs 5 in securing the ribs or stretchers in place, thereby insuring sufficient space for the movement of the end of the rib or stretcher, as will be 90 evident.

It is to be understood that the construction of the runner B is similar in all respects to the collar C.

It will be seen that by my construction any 95 particular rib or stretcher may be easily and quickly removed without disturbing the others.

It is obvious that the improvement is substantially the same whether used in connection with the notch-ring or the runner.

I am aware that a runner and a notch-ring having malleable projections compressed on an independent wire or ring have been pro-

posed. The present improvement avoids the use of such separate or independent wire and employs studs fixed to the rib or brace, as the case may be.

5 Having thus described my invention, what I claim as new, and desire to secure by Letters Patent, is—

In an umbrella, a notch-ring having two series of approximately radial projections of 10 malleable metal with comparatively wide bases and narrow points each of said series lying in a plane at a right angle to the longitudinal axis of the umbrella-stick and the 15 proximate projections of the series arranged in complemental pairs said pairs being arranged in groups of pins separated more

widely than the pins in each group, in combination with a series of ribs having their heads provided with studs, each rib having its head between the members of a pair and each 20 pair compressed upon a stud, whereby the parts may be freely assembled, and each rib independently fastened to the notch in a removable manner, and access for repair provided, all substantially as set forth. 25

In testimony whereof I have signed this specification in the presence of two subscribing witnesses.

ERWIN M. HARLEY.
